Patented Dec. 31, 1918.

FIG. 1

FIG. 2

FIG. 3

Richard C. Harris Inventor

By his Attorney
Emmy, Booth, Jammie & Harry

UNITED STATES PATENT OFFICE.

RICHARD C. HARRIS, OF NEWARK, NEW JERSEY.

CONTROL-SHEET FOR PNEUMATICALLY-OPERATED DEVICES.

1,289,465.

Specification of Letters Patent. Patented Dec. 31, 1918.

Application filed November 2, 1916. Serial No. 129,066.

To all whom it may concern:

Be it known that I, RICHARD C. HARRIS, a citizen of the United States, and a resident of the city of Newark, in the county of Essex and State of New Jersey, have invented an Improvement in Control-Sheets for Pneumatically-Operated Devices, of which the following is a specification.

This invention relates more particularly to note sheets for mechanical musical instruments, although its more general application to any traveling web of paper used to control pneumatic or other equivalent devices, will be apparent. The invention will be described in connection with mechanical musical instruments, as this is believed to be the principal field in which the invention may be used.

In player pianos or the like, a web of paper provided with perforations, is used to control the sounding of notes by pneumatically operated devices. This traveling web of paper or note sheet, as it is called, is wound upon a spool and in operation the note sheet is caused to travel over a tracker bar provided with holes or vents which may be selectively opened or closed by the note sheet. It is necessary that the note sheet lie snugly against the tracker bar in order to effect a substantially air tight closure of the vents which are not intentionally opened by perforations registering with certain selected vents. It is therefore considered essential that an extremely flexible paper be used in making the note sheet and to obtain the requisite flexibility, the paper is usually very lightly calendered. Such paper is very susceptible to expansion and contraction due to changing atmospheric conditions. If the paper is highly calendered it immediately becomes too stiff to unroll properly or to lie upon the tracker bar in satisfactory manner. Therefore, although a highly calendered paper might be stronger and would be subject to less expansion and contraction under changing atmospheric conditions, it cannot be used with satisfactory results. By means of the present invention, hereinafter described, a heavy, stiff, or highly calendered paper stock may be successfully used in the manufacture of the note sheets.

One embodiment of the invention is shown in the accompanying drawings, and therein, Figure 1 is a diagrammatic view illustrating the relative location of the essential parts of a mechanical musical instrument,

Fig. 2 is a fragmentary plan view of a note sheet embodying the invention, and

Fig. 3 is a greatly enlarged sectional view of the note sheet and tracker bar. 60

The present invention provides note sheet material which, more by reason of its structure than on account of its composition, is adapted to lie smoothly on the tracker bar and roll evenly upon or unroll evenly from 65 spools of small diameter.

In the drawings, Fig. 1 shows a music sheet spool 1, a tracker bar 2, and a take-up roll 3. To operate a musical instrument of the character herein generally referred to, 70 the note sheet, wound upon the spool 1, is placed in the instrument in the usual manner and connected with a hook 4 upon the take-up roll 3 by a ring 5, and during the operation of the machine the note sheet is un- 75 wound from the spool and wound upon the take-up roll thus causing it to pass over the tracker bar 2 and to selectively open and close vents 6 therein. It will be understood that the holes or vents 6 are connected with 80 certain pneumatic mechanisms, usually operated by suction through the tubes 11 so that when a perforation in the note sheet registers with a vent in the tracker a corresponding note will be sounded upon the instrument. Thus Fig. 1 serves to illustrate 85 the general conditions under which a note sheet is used.

It will be observed that the note sheet is originally wound upon a relatively small 90 spool. If the paper were stiff, this condition would normally tend to cause the paper to curl or to assume a normally rolled up condition even when free from the music spool. If such a condition obtained, the 95 paper would be very apt to arch up away from the tracker bar on account of the relatively slight tension exerted upon the paper by the drag of the music spool as the paper is being wound upon the take-up roll. And 100 furthermore the relatively low degree of suction usually employed will not securely hold the note sheet to the tracker bar when the paper tends to arch up away from the vents. Obviously, such a condition would 105 prevent the proper functioning of the note sheet in connection with the tracker bar vents.

Means are herein provided for increasing the longitudinal flexibility of the note sheet, 110 the same being shown as minute transverse corrugations or scorings of the note sheet

material. Referring particularly to Fig. 3 which is a greatly enlarged section through the note sheet and tracker bar, it will be seen that the note sheet material 7 is formed with 5 a plurality of transversely extending relatively thin portions 8 alternating with transversely extending relatively thick portions 9. In the specific embodiment of the invention herein shown, the under side 10 of the note 10 sheet lying against the tracker bar is relatively smooth and this is a preferable, though perhaps not essential condition. The transverse corrugations or scorings of the note sheet material shown herein, are such 15 as might be formed by passing the note sheet material between a pair of rolls, one a smooth surfaced roll and the other a corrugated roll. If sufficient pressure be exerted by one roll upon the other, the note sheet 20 material may be made to assume substantially the form herein shown.

It will now be readily seen that the thin transversely extending portions of the note 25 sheet form, in a sense, a great number of minute hinges which insure great longitudinal flexibility of the note sheet. This is accomplished without substantially weakening the note sheet material, due it is believed, to the highly compressed state of the paper 30 at the thinner portions thereof. In accordance with the present invention a highly calendered paper may be used, the structure of the paper counteracting if not entirely eliminating the inherent tendency of the highly 35 calendered paper to curl after it has been kept for some time in rolled condition. Because a highly calendered paper is much less susceptible to expansion and contraction on account of changing atmospheric conditions, 40 a note sheet of such stock will be superior to the ordinary note sheet. Furthermore in view of the fact that a highly calendered paper is generally stronger than a paper with a comparatively rough finish it may be 45 found practicable to use paper stock of lighter weight.

It may be further noted that a highly calendered paper is greatly to be preferred on account of the superior character of the perforations which may be cut therein. With 50

well compacted, highly calendered stock the perforations are cleaner in outline due to the more closely compacted condition of the fibers in the paper. Furthermore the lint or fuzz on lightly calendered stock oftentimes 55 is drawn into the tracker vents and eventually results in clogging up the vents and preventing or hindering proper action of the mechanism. The transverse corrugations which enable a highly calendered stock to be 60 used may, it is believed, actually increase the transverse resiliency of the note sheet.

It is to be understood that the invention may be variously modified and embodied 65 within the scope of the subjoined claims.

I claim as my invention:

1. A perforated control sheet, for pneumatically operated devices, varying in thickness and having transversely extending thin portions alternating with transversely extending relatively thick portions extending substantially across the entire width of the sheet.

2. A perforated control sheet, for pneumatically operated mechanisms, which have 75 a spool, tracker bar and take-up roll, comprising a paper sheet having a smooth back to contact with the face of the tracker bar and a corrugated face, said corrugations extending transversely of the line of travel of 80 the sheet, to increase the longitudinal flexibility of the sheet.

3. A note sheet for mechanical musical instruments, having note sounding perforations and being scored transversely across 85 substantially the entire width of the sheet to increase the flexibility of the note sheet on the lines of the transverse scorings.

4. A note sheet for mechanical musical instruments, of relatively highly calendered 90 paper stock, having note sounding perforations therein and having a plurality of corrugations in the note sheet material extending substantially across the entire width of the sheet, thereby increasing the longitudinal 95 flexibility of the note sheet.

In testimony whereof, I have signed my name to this specification this 31st day of October, 1916.

RICHARD C. HARRIS.
